PIVOTED VERTICAL GATE
C D Lowrey, Quitman, La., assignor to
C. D. Lowrey & Company, Inc.
Filed Dec. 6, 1962, Ser. No. 242,716
6 Claims. (Cl. 39—82)

This invention relates to a novel and useful pivoted gate and more specifically to a gate primarily designed for use as a swingable closure for the rear end of truck bodies.

When loading and unloading stock the driver of a mobile stock pen usually backs up to a stock delivery chute. If the mobile stock pen is provided with a conventional type of gate which is swingable about an upstanding axis, the driver must stop short of the discharge end of the delivery chute, dismount and open the gate, and then remount the mobile stock pen and back up the remaining distance to the discharge end of the delivery chute. By providing a gate which is pivoted for movement about an axis extending transversely of the medial plane of the gate, the mobile stock pen may be backed up to a point immediately adjacent the discharge end of a stock delivery chute. Then, the driver has only to pivot the gate about its horizontally disposed axis in order to allow stock to travel from the discharge chute into the mobile stock pen.

It is accordingly the main object of this invention to provide a new and useful gate which may be utilized as the closure member for the rear end of mobile stock pens and which is mounted for swinging movement about a horizontally disposed axis extending substantially normal to the medial plane of the gate.

Another object of this invention, in accordance with the preceding object, is to provide coating guide means carried by the swingable gate member and the upstanding gate post to which it is pivotally mounted for guiding the free swinging portion of the gate member against movement laterally of its medial plane during its swinging movement between the upper open position and the lower closed position.

Still another object of this invention, in accordance with the immediately preceding object, is to provide a swingable gate which is also mounted for swinging movement relative to the afore-mentioned gate post about an upstanding axis in a conventional manner in order that the gate may also be used as a conventional gate.

Still another object of this invention is to provide a pivoted gate member in accordance with the preceding objects which will also be readily adaptable for use in environments other than as a swingable closure for the rear end of a mobile stock pen.

A final object of this invention to be specifically enumerated herein is to provide a pivoted vertical gate in accordance with the preceding objects which will conform to conventional forms of manufacture, be of simple construction and easy to handle so as to provide a device that will be economically feasible, long lasting and relatively trouble free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a fragmentary top plan view of the rear end of a mobile stock pen shown with the pivoted vertical gate of the instant invention being utilized as a closure for the rear end of the stock pen;

FIGURE 2 is a fragmentary rear elevational view of the embodiment illustrated in FIGURE 1;

2

FIGURE 3 is a fragmentary side elevational view of the embodiment illustrated in FIGURE 2 as seen from the left side of FIGURE 2;

5 FIGURE 4 is an enlarged fragmentary vertical sectional view taken substantially upon the plane indicated by the section line 4—4 of FIGURE 2;

FIGURE 5 is an enlarged fragmentary vertical sectional view taken substantially upon the plane indicated by the section line 5—5 of FIGURE 2;

10 FIGURE 6 is a rear elevational view similar to that of FIGURE 2 but on somewhat of a reduced scale and showing the gate member in a raised open position;

FIGURE 7 is a fragmentary side elevational view of a modified form of gate showing the manner in which it is also pivotally secured to the corresponding gate post for movement about an upstanding axis in order that the gate may also be utilized as a conventional gate;

15 FIGURE 8 is a vertical sectional view taken substantially upon the plane indicated by the section line 8—8 of FIGURE 7 and with an open position of the gate member being shown in phantom lines;

20 FIGURE 9 is an enlarged fragmentary horizontal sectional view taken substantially upon the plane indicated by the section line 9—9 of FIGURE 7;

25 FIGURE 10 is a fragmentary rear elevational view of a further modified form of gate member which is similar to that illustrated in FIGURES 1 through 5 but which utilizes additional guide means for guiding the free swinging portion of the gate member against lateral movement;

30 FIGURE 11 is an enlarged fragmentary vertical sectional view taken substantially upon the plane indicated by the section line 11—11 of FIGURE 10; and

35 FIGURE 12 is a fragmentary side elevational view illustrating a modified form of latch for the gate.

Referring now more specifically to the drawings, the numeral 10 generally designates the flooring of a mobile stock pen which is provided with a pair of upstanding sides 12 and 14 including gate posts 16 and 18 respectively at corresponding ends of the sides 12 and 14.

40 The pivoted vertical gate assembly of the instant invention is generally designated by the reference numeral 20 and includes a generally rectangular gate member 22. The gate member 22 includes a pair of upstanding side members 24 and 26 which are interconnected by means of a plurality of generally parallel horizontal members 28. In addition, the horizontal members 28 are interconnected by means of an additional pair of vertical brace members 30 which are spaced inwardly from the 45 upstanding side members 24 and 26.

45 The lower end portion of the gate post 16 has a journal block 32 mounted thereon in any convenient manner such as by welding 34 and a pivot pin 36 projects from the inside face of the gate member 22 and is rotatably received in the journal block 32. In this manner, the 50 gate member 22 is mounted for swinging movement about a generally horizontally disposed axis extending transversely of the medial plane of the gate member 22 defined by the pivot pin 36.

55 An arcuate guide member 40 is secured in spaced relation to the inside face of the gate member 22 by means of mounting studs 41 secured between the gate member 22 and the arcuate guide member 40. A grooved guide wheel or follower 42 is rotatably journaled from the upper end 60 of the gate post 16 by means of a pivot pin 44 and it will be noted from FIGURE 4 of the drawings that the grooved guide wheel or roller 42 is disposed in rolling contacting relation with the outer peripheral surface 46 of the arcuate guide member 40 and that the flanges 48 and 50 defined 65 by the groove 52 formed in the wheel 42 are disposed on opposite sides of the arcuate guide member 40. It will be noted that the axis of rotation of the gate mem- 70

ber 22 defined by the pivot pin 36 defines the center of curvature of the arcuate guide member 40. Additionally, the opposite ends of the arcuate guide member 40 each have a radially outwardly projecting abutment 54 secured thereto for engagement by the wheel or roller 42 in order to limit swinging movement of the gate member about the longitudinal axis of the pivot pin 36 in both directions.

From FIGURES 1, 3, and 6 of the drawings, it may be seen that an upstanding guide bracket 58 is secured to the gate post 18 and defines, together with the latter, an upwardly opening channel in which the lower edge of the gate member 22 is receivable when the gate member 22 is moved toward its lowered and closed position illustrated in FIGURES 2 and 3 of the drawings. The bracket 58 includes an L-shaped member 59 including horizontal and vertical legs 60 and 61, the free end of the horizontal leg 60 is secured to the gate post 18 and a pair of brace members 62 are secured between the gate post 18 and the vertical leg 61 at points spaced longitudinally therealong. The upper edge of the uppermost brace member 62 has an upwardly opening notch 63 formed therein in which a generally horizontal hooked abutment member 64 is seatingly engageable for defining the closed position of the pivoted gate member 20. In addition, a cam strap 65 is provided and extends between portions of the gate post 18 and the leg 61 for camming the free edge of the gate member 22 into engagement with the vertical leg 61 as the gate member 22 is pivoted to the closed position.

With attention now directed to FIGURES 7 through 9 of the drawings, there will be seen a modified form of mobile pen generally referred to by the reference numeral 66 which includes a gate post 68 corresponding to the gate post 16. However, the journal block 70 of the stock pen 66 is fixed to a sleeve 72 being rotatably supported from the gate post 68. The journal block 70 corresponds to the journal block 32 and the pivot pin 74 of a gate member 76 which is identical to the gate member 22 is rotatably received in the journal block 70. In addition, the pivot pin 78 by which the grooved wheel 80 corresponding to the grooved wheel 42 is rotatably supported from the gate post 68 is secured to a sleeve 82 which is also rotatably supported from the gate post 68. Accordingly, it may be seen that the gate member 76 may be pivoted to an open position similar to the open position of the gate member 22 illustrated in FIGURE 6 of the drawings and also to an open position swung about an upstanding axis defined by the gate post 68 in a conventional manner.

If it is desired, the gate members 76 and 22 may be secured in the lowered positions illustrated in FIGURES 7 and 3 of the drawings by means of locking pins 84 and 86 passed through pairs of aligned bores 88 and 90 formed in the gate member 76 and the gate post 68 and bores 92 and 94 formed in the gate member 22 and the gate post 16.

With attention now directed to FIGURES 10 and 11 of the drawings, there will be seen a further modified form of mobile pen generally referred to by the reference numeral 96 which includes a gate member generally referred to by the reference numeral 98 that is substantially identical to the gate member 22 with the exception being that the arcuate guide member 100 thereof is also provided with a longitudinally extending slot 102. In addition to the guide follower or grooved wheel 104 which corresponds to the grooved wheel 52, the mobile pen 96 includes a guide shank 106 which is fixedly secured to the gate post 108 corresponding to the gate post 16 and it may be seen that the guide shank 106 extends through and is slidably received in the slot 102.

As the mobile pen 96 is otherwise substantially identical to the mobile pen 10, further explanation of the second modification is deemed to be unnecessary.

In FIGURE 12 there may be seen a modified form of locking means which may be used in lieu of the locking pins 84 and 86 and is designated by the reference numeral 110. The locking means 110 includes a pair of general-

ly U-shaped members 112 and 114 secured to the gate post 16' and the side member 24'. The members 112 and 114 include pairs of apertured legs 116 and 118 respectively and the legs 116 and 118 include registrable bores 120 and 122 respectively through which a locking pin 124 may be passed.

The upper portions of the rear ends of the sides 14 and 16 are interconnected by means of an inverted U-shaped brace assembly generally referred to by the reference numeral 126 including a pair of depending legs 128 and 130 interconnected at their upper ends by means of a bight portion 132. The legs 128 and 130 each include a large diameter tubular lower leg section 134 and an upper small diameter leg section 136 telescopingly within the upper end of the corresponding lower section 134 and removably secured in adjusted positions by means of a set screw 138 carried by the corresponding lower section 134. The bight portion 132 rigidly interconnects the upper ends of the upper sections 136.

In operation, each of the gate members 22 and 98 may be swung to the open positions from the closed positions illustrated in FIGURES 2 and 10 of the drawings merely by swinging the gate members 22 and 98 about their respective axes of rotation. In addition to being able to be swung to the open position in the same manner as the gate members 22 and 98, the gate member 76 may also be swung to an open position in the conventional manner about an upstanding axis defined by the gate post 68. Inasmuch as the guide or follower wheel 80 is also swingably supported from the gate post 68, the coaxing guide means defined by the guide follower wheel 80 and the corresponding arcuate guide member 81 may be maintained in constant guiding engagement with each other.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. In combination with first and second upstanding sides disposed alongside each other and terminating at corresponding rear ends in first and second posts, respectively, including confronting inner sides, an upstanding gate member including a pair of normally upstanding opposite edge portions, means pivotally securing said gate member, at a lower portion of one of said upstanding edge portions, to said first post for swinging movement of the other upstanding edge portion of said gate member about a generally horizontally disposed axis disposed transversely of said gate member between a lower closed position and an upper open position, said means being pivotally supported from said first post for rotation about an upstanding axis spaced forwardly of the vertical plane in which said gate member is swingable about said horizontal axis when said gate member is in said closed position.

2. The combination of claim 1, said second gate post includes an upstanding guide bracket adjacent its lower end generally parallelling said second gate post and defining, with the latter, an upwardly opening channel in which the lower edge of said gate member is receivable when said gate member is moved toward its lowered closed position.

3. The combination of claim 1 including coaxing guide means supported from said gate member and a portion of said first post disposed above said axis, engaged with each other and guiding the free swinging portion of said gate member against lateral movement, said guide means supported from said first post also being mounted on said first post for rotation about an upstanding axis generally coinciding with the upstanding axis of rotation of said gate member.

4. The combination of claim 3 wherein said coating guide means includes a arcuate guide member secured to said gate in a position having said horizontal axis as its center of curvature and a guide follower supported from said post and guidingly engaged with said guide member.

5. The combination of claim 4 wherein said guide follower comprises a grooved wheel journaled for rotation from said first post and disposed in rolling contacting engagement with said arcuate guide member.

6. The combination of claim 5 wherein said grooved wheel is disposed in rolling contacting engagement with the outer periphery of said arcuate guide member.
